UNITED STATES PATENT OFFICE.

CYRUS W. SALADEE AND WILLIAM BAUDER, OF CIRCLEVILLE, OHIO.

IMPROVEMENT IN TOP IRONS AND PROPS FOR CARRIAGES.

Specification forming part of Letters Patent No. **86,696**, dated February 9, 1869.

To all whom it may concern:

Be it known that we, CYRUS W. SALADEE and WILLIAM BAUDER, both of Circleville, in the State of Ohio, have invented a new and Improved Mode of Constructing Top Irons and Props for Supporting and Adjusting Tops to Carriages and Buggies; and we do hereby declare that the following is a full and exact description thereof, reference being had to the accompanying drawings, and to the letters of reference marked thereon.

The nature of our invention consists in the peculiar manner of supporting and adjusting tops to carriages and buggies, substantially as hereinabove shown and described.

Tops to carriages and buggies as now generally constructed lack one important consideration for the support of that portion of them between the two back bows, E^3 and E^4 , (Figure 1,) the lower prop-iron, C, Fig. 1, invariably extending up and taking hold of the third bow, E^3 , and the front prop-iron, A, extending from bow E^3 to the front bow, E' , and thus the leather covering the top from the bow E' to E^3 is properly strained and supported; but from the latter mentioned bow to the back one, E^4 , there is no such support, and hence this back quarter of the top is continually drawing out of shape. Now, to remedy this defect we apply the short quarter prop-iron B (see Figs. 1 and 2) with a joint, 2, and the front end of which has a square hole, as shown in Fig. 2. To the back edge of the bow E^3 is secured the prop T, (shown in Fig. 4,) and through which is passed the bolt of the lever D, and which is provided with a square corresponding to the square hole in the front of the iron B. This bolt of the lever D is passed through from the inside of the top. The short iron B is then placed in position as shown in Fig. 1. We next apply the lower prop-iron, C, the top end of which is also provided with a square hole, (see Fig. 2,) and made to fit upon the same square of the bolt of lever D; and, last, the front prop-iron, A, is placed upon the same bolt, the end of which is made round for the reception of this iron. Figs. 3 and 4 show the order in which those irons B C A are ar-

ranged upon the bolt of the lever D. While, therefore, we have the top completely strained and supported from the bows E' to E^4 , we combine therewith the advantage of adjusting the irons C and B from the inside of the top by means of the lever D seen in Figs. 1, 3, and 4.

The operation of the complete top with the irons arranged as herein shown and described is as follows, viz: Supposing the top to be up, as shown in Fig. 1, when, to let it down, the person on the seat has only to lay hold of the lever D, and by a slight downward pressure the joint 2 of the prop-iron B and the joint 3 of the lower prop-iron, C, are broken in the direction of the dotted lines 5 and 6, when the top is let back and the two bows E^3 and E^4 are allowed to fold together, the same as in tops not having the quarter prop-iron B; and to raise the top this order of proceeding is reversed.

These prop-irons B and C may be used with or without the lever D, just as we may elect.

We are aware that the simple application of a short stiff quarter prop-iron is not new; and we are also aware that the use of the lever D (shown in the drawings) for the purpose of adjusting the lower prop-iron of ordinary tops is old and well known, and to either of these devices, separately, we lay no claim; but

We do claim, broadly, as new, of our invention, and desire to secure the same by a grant of Letters Patent—

1. The combination of the prop-irons B C and top-prop T, constructed substantially as described, and operating as and for the purposes set forth.

2. The combination of the lever D with the prop-irons B C and top-prop T, constructed substantially as described, and operating as and for the purposes set forth.

CYRUS W. SALADEE.
WM. BAUDER.
